COPYING DEVICE

Werner Schindler, Biel, Switzerland

Application November 4, 1943, Serial No. 508,982
In Switzerland September 8, 1942

1 Claim. (Cl. 90—13.5)

1

My invention relates to improvements in copying devices for the operation of automatics, machines and apparatus by photo-electric cells; and the objects of my improvement are, first, to replace the templets used heretofore in such copying processes by a drawing or photo of the work piece to be copied, second, to materially reduce the costs of copying, and third, to speed up the copying process.

Heretofore machine tools and other machines, automatics and apparatus for series work have been mechanically controlled by expensive templets or patterns in connection with the copying process. The manufacture of such templets however, requires much time, great accuracy, and often is too costly for small or middle size series work.

The inventive idea of my present invention is to replace such templets by an accurate, yet cheap, plan, e. g. a drawing to any chosen scale or a photo of the workpiece to be copied, which is laid upon a photocell or projected thereon by suitable optical means, and the outlines of which are controlled by a light ray thereby automatically controlling the movements of the machine part.

I attain these and related objects by the mechanism and installation illustrated in the accompanying drawing, in which—

Fig. 1 is a schematic plan of the complete apparatus of the copying device, comprising an electrical and hydraulic transfer mechanism; Fig. 2, the electrical transfer mechanism comprising a servo-motor; Fig. 3, the electrical transfer mechanism adapted as motor-generator aggregate; Fig. 4, a detail of the transfer mechanism comprising an electromagnet acting upon the hydraulic portion; and Fig. 5, an electrically controlled magnet acting directly upon the machine part to be operated.

The source of light produces a lightray undisturbed by the daylight and is fed, together with the amplifier 2, by the electrical net mains N. The photocell 3, which is connected with the amplifier 2 and exposed to the said lightray, may be secured to the cylinder 4 which is freely supported and upon which the operating machine part is mounted. The cylinder 4 and its piston 5 are slidably mounted on or in each other in a longitudinal sense. The piston 5 is anchored at its outer end to a stationary point 6, while the cylinder 4 is movable and is normally urged in one direction by a constant mechanical pressure, produced, for example, by a pressure spring or a counterweight. The cylinder is moved in the opposite direction by hydraulic pressure and by

2

varying this hydraulic pressure, the position of the movable cylinder relative to the piston is changed. In Figure 1 a spring 4a is shown for applying a constant force to the cylinder 4.

The current impulses generated in the photocell, carried over at least one amplifier into the line 11, operate the electrical transfer mechanism, e. g. an electrical servo-motor 9 with forward and backward rotation, the shaft of which may turn in each sense of rotation up to 90 degrees and is coupled with a hydraulic bypass control valve 7. The angular throw of the shaft is adjustable in order to open the bypass valve 7 more or less and thus to regulate the oil quantity fed by the pressure pump 8 into the cylinder 4 for the purpose of displacing the cylinder relative to the stationary piston 5.

The plan 10 of the form of line to be copied is laid upon the photocell 3, or respectively projected thereon, and the cylinder 4 is displaced crossways under the light-source 4. When the controlling lightray projects through the plan or drawing 10 onto the photocell 3, the amplifier 2 is excited, the servo-motor 9 rotated, the bypass control valve 7 opened, the pump 8 delivers oil into the left hand end of the cylinder 4, and the latter—together with the machine part to be operated—will recede from the point of attachment 6 for the piston. When, however, the controlling lightray strikes upon the said form of line, it will act less or not at all upon the photocell 3, i. e. the motor 9 rotates backward, the valve 7 is opened less, the pump 8 feeds less oil, and the cylinder 4 is displaced toward the fixed point 6 by virtue of the now prevailing constant mechanical pressure. The movement of the cylinder 4 and of the machine part connected thereto doing the copying work, corresponds to that of the line on the plan which is successively controlled by the lightray.

The device also may comprise a freely movable piston, upon which the photocell and the machine part to be operated are mounted, in which case the cylinder is stationary.

Fig. 2 illustrates another form of mechanical transfer mechanism between the electrical servo-motor and the control valve of the hydraulic part. The current impulses generated in the photocell and carried over the amplifier into the lines 11 act upon an electrical servo-motor 12 for forward and backward rotation, the pinion 13 of which engages the gear segment 14. The latter is rockably mounted in the shaft 15 and its arm 16 again opens the bypass valve 7 more or less, thereby automatically changing the oil volume

of a hydraulic control device, as described above, and automatically controlling the position of the cylinder 4 relative to the piston 5 and thus also the movement of the said machine part. The servomotor is restored to its initial position by the valve 7, this valve being subjected to the action of a restoring spring the pressure of which is increased when the valve opens.

According to Fig. 3, the electrical transfer mechanism also may comprise an electric motor 17 coupled to a dynamo, the housing of which is rotatively mounted. The current impulses carried from the photocell over the amplifier through the lines 11 act upon the exciting winding of the dynamo. The housing of the latter thus is rotated more or less, and the bypass valve 7, which is connected to the transfer member (adapted e. g. as shown as grooved pulley 18), is opened more or less. In this manner the oil volume of a hydraulic control device is changed and, as described above, the motion of the machine part is automatically controlled. The housing 18 is prevented from rotating continuously by the grooved pulley 19 which is coupled with the valve 7. The valve 7 is placed under the action of a restoring spring which tends to restore it in its closed position; the valve is opened when increasing the traction of the housing; if this traction becomes smaller than the restoring pressure of the spring, the housing will be restored by the valve to its initial position. The output of the motor is constant; the housing is rockably supported and prevented from rotating continuously by the valve 7 through the pulley 19. The armature rotating in the housing is coupled with the motor. If the winding of the housing is excited more or less in dependence upon energization of the photo-cell, the housing will rotate more or less, thus opening the valve more or less against the action of the restoring spring thereof. The current supplied by the dynamo varies with the latter's excitation and could be used for exciting an auxiliary bigger dynamo in order to attain still greater variations of the current impulses.

The further form of electrical transfer mechanism shown in Fig. 4 comprises an electric vertical magnet with the winding 20 and the core 21. The current impulses generated in the photocell 3 and carried over the amplifier 2 into the lines 11 act upon the winding 20 to attract the

core 21 more or less. The bypass valve 7 connected to the latter thus is opened more or less to vary the oil volume of a hydraulic control device. In this way, as described before, the motion of the machine part is automatically controlled.

According to Fig. 5, the copying device also may comprise an electrical transfer mechanism without any hydraulic portion. In this case the 10 current impulses, generated in the photocell 3 and carried over the amplifier 2 and through the lines 11 into the winding 22 of an electric vertical magnet, act upon the latter to attract its core 23. The latter operates the machine part 24 either directly, or indirectly by displacing the work piece.

The copying device described mainly is suited for milling, grinding, boring, turning and similar machine tool operations for series work.

What I claim and desire to secure by Letters Patent is:

In a copying device, a movable cylinder, a pattern supporting means movable with said cylinder, a stationary piston in said cylinder, a fluid pump, a fluid conduit connecting said pump with 25 said cylinder for supplying pressure fluid thereto, means opposing the pressure fluid, a control valve interposed in said conduit, a pattern tracer controlled servo-motor for regulating said valve 30 said servo-motor including a motor-generator aggregate in which a generator housing is rockably supported and means on said housing for actuating said valve, said housing rotating in dependence upon energization of the photo-cell 35 through the armature of the generator coupled with the motor.
